CLAIM

The ornamental design for a sterile cover for an ocular portion of a medical device, as shown and described.

DESCRIPTION

FIG. 1 is an isometric view of a sterile cover for an ocular portion of a medical device;

FIG. 2 is another isometric view thereof;

FIG. 3 is a top view thereof; and,

FIG. 4 is a bottom view thereof.

The broken lines illustrate portions of the sterile cover for an ocular portion of a medical device that form no part of the claimed design.
